TRANSCEIVER SYSTEM

Murray G. Crosby, Riverhead, N. Y., assignor to
Radio Corporation of America, a corporation
of Delaware

Application February 15, 1943, Serial No. 475,896

11 Claims. (Cl. 250—13)

1

My present invention relates to communication systems of the transceiver type, and more especially to a transceiver utilizing frequency modulation.

One of the main objects of my present invention is to provide a transceiver system which functions to receive either frequency modulated (FM) carrier wave energy or amplitude modulated (AM) carrier energy by super-regenerative detection, and which employs a detection stage as a master oscillator for the production of frequency modulated carrier wave energy during the transmission function.

Another important object of this invention is to provide a radio signalling system which functions to receive angle modulated carrier wave energy by means of super-regenerative detection, there being employed an auxiliary network in association with the signal input circuit of the super-regenerative detector to produce angle modulated carrier wave energy for the purpose of transmitting.

Another important object of my invention is to provide an FM carrier wave transceiver system which is economical in its use of electron discharge tubes, and employs a minimum of components whereby it readily lends itself for compact assembly.

Other objects of my invention are to provide a transceiver system, particularly adapted for receiving either AM or FM signals, which is compactly constructed and assembled so that the system may be employed as a so-called "walkie-talkie" receiver for military application, or for disposition in mobile units such as tanks, airplanes or marine units wherein space is at a premium.

Still other objects of my invention are to improve generally the simplicity and efficiency of FM transceiver systems, and more especially to provide an FM transceiver which is not only durable and reliable in operation, but is economically manufactured and assembled.

The novel features which I believe to be characteristic of my invention are set forth with particularity in the appended claims; the invention itself, however, as to both its organization and method of operation will best be understood by reference to the following description, taken in connection with the drawing, in which I have indicated diagrammatically a circuit organization whereby my invention may be carried into effect.

In the drawing:

2

Fig. 1 shows a system embodying the invention.

Fig. 2 graphically illustrates the effect of tube 10 on circuit S during signal reception.

Referring now to Fig. 1 of the accompanying drawing, wherein I have shown the circuit diagram of one illustrative embodiment of my invention, the signal collector 1 is coupled by condenser 2 to the high potential side of a signal input circuit S. The signal input circuit consists of coil 3 connected in shunt with the adjustable tuning condenser 4. The low potential side of the signal input circuit S is established at an invariable alternating potential, such as ground. There are provided a pair of electron discharge tubes 5 and 6. These tubes are illustrated as being of the triode type; the invention is not limited to these particular types of tubes. The cathodes of tubes 5 and 6 are connected to a common lead; the latter is connected to a predetermined intermediate tap point 7 on the input coil 3. The control grids of tubes 5 and 6 are connected in common to the grid terminal of a direct current blocking condenser 8. The opposite terminal of condenser 8 is connected to the high potential side of input circuit S. The grid return resistor 9 is connected between the common grid connection of the tubes 5 and 6 and the common cathode connection thereof.

The plate of tube 5 is designated by numeral 10. It is connected to a predetermined point on the direct current voltage supply bleeder 11 through a path which comprises filter choke coils 12 and 13, a primary winding 14 of the audio output transformer 15, lead 16, switch arm 17 and the adjustable tap 18. The voltage supply bleeder 11 has one end thereof grounded, while the opposite end is connected to the positive terminal +B of the direct current source. Switch arm 17 may be adjusted to either of two contact points 19 or 25. Contact point 19 is connected to the adjustable slider 18, while contact point 25 is connected to the positive end of the voltage supply resistor 11. Radio frequency bypass condensers 20, 21, and 22 connect the ends of series filter chokes 12 and 13 to ground. The network 12—13—20—21—22 functions as a radio frequency and quench frequency filter network to prevent any radio and quench frequency components from passing to the primary winding 14.

The plate 10' of tube 6 is connected to the lead 16 through a filter network which is similar to that just described in connection with the plate circuit of tube 5. Hence, the series choke coils are represented by numerals 12' and 13', while

the bypass condensers are designated by numerals 20', 21' and 22'. The second primary winding of transformer 15 is denoted by numeral 14', and its ends are connected to a pair of contacts 30 and 31. The contact point 31 is connected to the upper end of winding 14' which has a contact point 31'. The contact point 30 is connected to the lower end of winding 14' which has a contact point 30'. Further, contact points 30 and 31 are the contact points for one position of a double-pole, double-throw switch arm 32. The contact points 31' and 30' are the contact points which receive the switch arm 32 in the opposite position thereof. One terminal of switch arm 32 is connected to the junction of choke coil 13' and condenser 22'. The other terminal of the switch arm is connected to the lower end of primary winding 14'.

When the switch arm 32 is adjusted to contact points 30 and 31, then the primary winding 14' has one polarity relative to the winding 14. When the switch arm 32 is in the opposite position, then the winding 14' has its polarity reversed. More specifically, the former position is the push-push connection for windings 14 and 14', while the latter is the push-pull connection. The secondary winding of transformer 15 is designated by the numeral 15'. Any desired form of audio utilization network may be connected to the terminals of winding 15'. For example, one or more stages of audio amplification followed by a reproducer such as a loud speaker or head phones may be used. In the case of a "walkie-talkie" receiver, head phones could be plugged directly between the ends of winding 15'.

The detector tubes 5 and 6, by virtue of their common cathode connection to the resonant circuit S, function as an oscillating detector system. In other words, the tubes are connected with their input electrodes in parallel in an oscillator circuit of the Hartley type. Detection will occur by virtue of grid leak detection, because of the condenser 8 and grid leak resistor 9. Super-regenerative detection action is secured by means of the quench oscillator network now to be described.

The quench oscillator circuit comprises a pair of electron discharge tubes which are designated by numerals 40 and 41, and these tubes are shown as triodes by way of illustration. For the sake of compactness of construction both tubes 40 and 41 may be mounted within a single tube envelope, as in the case of the well-known twin triode type of tube. This may also be true in the case of the tubes 5 and 6. The plates 42 and 43 of tubes 40 and 41 respectively are connected to opposite sides of a resonant tank circuit comprising coil 44, shunt tuning condenser 45 and condensers 20-20'. The cathodes of tubes 40 and 41 are connected in common to ground, while the control grids are connected to ground through respective grid leak resistors 46 and 47. The grid end of resistor 46 is cross-connected by direct current blocking condenser 46' to the plate 43, while the direct current blocking condenser 47' connects plate 42 to the grid end of resistor 47.

The plates 42 and 43 are connected to a common source of direct current voltage by means of a lead 48. The latter has one end thereof connected to the midpoint 49 on coil 44. The opposite end of lead 48 is connected to an adjustable switch element 50 which is adapted to be adjusted to either contact point 51 or contact point 52. The contact point 52 may be connected to a voltage slider 53 adapted to be ad-

justed over the voltage supply resistor 54. The latter has one end thereof grounded, while the opposite end thereof may be connected to the positive terminal +B of the direct current source.

5 The bypass condenser 55 connects the lead 48 to ground.

The resonant circuit 44-45 may be tuned to any super-audible frequency, as, for example, to a frequency of the order of 100 kilocycles (kc.). 10 The tubes 40 and 41 and the circuits associated therewith provide a push-pull type of oscillator. The latter applies its oscillatory output energy in alternating fashion to the plates 10 and 10' of detector tubes 5 and 6 respectively. Thus, one end of coil 44 is coupled by means of the direct current blocking condenser 60 to plate 10, while the direct current blocking condenser 61 connects plate 10' to the opposite end of coil 44.

When the switches 17-19 and 50-52 are closed, then the tubes 5 and 6 function in the manner of a super-regenerative detector. The signal collector device 1 may be a relatively short rod, as is customary in the case of mobile compact receivers, or it may be a dipole unit. The signal circuit S, in the case of reception of FM signals, will be tuned to the mean frequency F_m of the desired FM transmitter. I do not wish to restrict the present invention to any particular band of reception, since the invention will function to receive FM signals in any of the megacycle (mc.) ranges. In the usual form of prior FM detector circuit there has been employed a pair of input circuits oppositely mistuned relative to the mean frequency of received FM signals. 35 There has, also, been utilized a phase shift network to provide frequency discrimination. In the present system I provide a form of "sweep" frequency discrimination under the control of the quench oscillator.

40 In other words, the tuning instrumentality 4 is initially adjusted, assuming that quench oscillations are not being applied to plates 10 and 10', so that circuit S is tuned to the mean, or carrier, frequency F_m of the incoming FM signal energy. The alternately applied quench energy from the quench oscillator is then employed alternately, and according to a predetermined sequence, to shift the reactive effect produced by a reactance tube 70. The latter acts to detune the circuit S at a superaudible rate to either side of the mean, or normal, frequency of circuit S. During reception of FM signals the plates 10 and 10' of the super-regenerative detector tubes 5 and 6 are in push-pull relation. That is, switch 32-31'-30' is closed. Should AM carrier signals be received, then the switch arm 32 would be adjusted to its opposite position so that the windings 14 and 14' would be of such polarity that the plates 10 and 10' would be connected in push-push fashion.

55 Returning to the reactance tube 70, the latter is illustratively depicted as of the pentode type. It may be a simple triode tube. The cathode 71 is connected to ground through the usual grid biasing network 72, while the plate 73 is connected to a point of positive potential +B through the radio frequency choke coil 74. The lower end of coil 74 is bypassed to ground by condenser 75. Plate 73 is coupled to the high potential side of circuit S by condenser 76. It is, also, connected to the control grid 77 by means of the direct current blocking condenser 78. The grid return resistor 79 connects grid 77 to an adjustable slider 80 of potentiometer 81. One end of the potentiometer resistor 81 is connected to

ground. Condenser 82 is connected between the upper end of slidable arm 80 and ground. The opposite end of resistor 81 is connected to switch arm 83 which is adapted to be adjusted to either of contact points 84 or 85. Switch 83-85 is closed during reception of signals. In the closed position of the switch the coupling condenser 86 connects contact point 85 to the coil 44 of the quench oscillator.

The contact point 84 is connected to ground through the secondary winding 90 of a modulation input transformer 91. The primary winding 92 of transformer 91 has one end thereof connected to the input microphone 93. The opposite terminal of the microphone is connected to the opposite end of winding 92 through a negative biasing voltage source 94. The tube 70 produces a capacitative effect across the resonant circuit S by virtue of the phase shifter network 78-79. As is well known to those skilled in the art, there is developed across resistor 79 alternating voltage which is in phase quadrature with the alternating voltage existing at plate 73 of tube 70.

This is due to the fact that condenser 78 and resistor 79 are arranged in series between plate 73 and cathode 71, and the magnitude of resistor 79 is low compared to the reactance of condenser 78. Under these conditions the plate to cathode impedance of tube 70, which is in shunt across resonant circuit S, produces a capacitative reactance effect across the resonant circuit S. The magnitude of the reactive effect is a function of the transconductance of tube 70. Since the quench oscillatory energy is applied to the grid 77 of tube 70 when switch 83-85 is closed, it follows that the gain of tube 70 will vary at the superaudible frequency rate of the quench oscillator. Hence, the reactive effect of tube 70 across resonant circuit S will vary at the same superaudible rate. Of course, the invention is not limited to the production of a capacitative reactive effect across S, since the effect could be inductive by a proper change in the phase shifter network.

Considering, again, the application of the quench oscillations to detector tubes 5 and 6 in alternate manner, it will be clear that when quench oscillations are applied, for example to tube 5, the same oscillatory quench energy at that instant will be applied to grid 77 of reactance tube 70. Thus, there will be produced a capacity effect across input circuit S of such a value that the resonance curve of circuit S will be shifted to one side of the mean frequency F_c of incoming FM signals. On the other hand, when the quench oscillator applies its oscillatory energy to the opposite tube 6, the reactance tube 70 will be caused to produce concurrently a capacity effect across input circuit S such that the resonance curve of the latter will now shift to the opposite side of the mean frequency of the FM signals. In Fig. 2, which is self-explanatory, this action is graphically depicted. There is produced the same effect as would be the case were each of tubes 5 and 6 provided with its own respective input circuit, and the input circuits were oppositely and equally mistuned relative to the mean frequency F_c of incoming FM signals.

In other words, the quench oscillator is employed to control the reactive effect produced by tube 70 in such a manner that "sweep" frequency discrimination occurs at input circuit S thereby to provide the required conversion of the FM signals into corresponding AM signals. The latter are readily rectified by the super-regenerative

detector tubes 5 and 6, assuming the plate circuits are connected in push-pull relation. Reference is made to my copending application Serial No. 446,876, filed June 13, 1942, particularly Fig. 4, for a more detailed explanation of the functioning of a "sweep" frequency discrimination network of this type.

Should the receiver be employed to receive AM carrier energy it would only be necessary to throw switch 32 into push-push position. That is, switch 32-30-31 is closed. The tuning means 4 would then be adjusted so as to tune circuit S to the carrier frequency of the incoming AM signals. Super-regenerative detection would be provided by virtue of the application of the quench oscillations in alternate fashion to the plates 10 and 10'. AM detection would not be affected by the "sweep" action of the reactance tube 70, because the mean frequency of circuit S would be the AM carrier frequency. For a somewhat more selective type of AM reception switch 83 may be opened to prevent the variation of the capacity effect of tube 70 by the quench oscillator. In other words, tube 70 may be in or out of circuit with resonant circuit S for AM reception.

The receiver is readily transformed into a transmitter of FM signal energy by simultaneously adjusting switch arms 83, 50 and 17 into contact with respective contact points 84, 51 and 25 respectively. When switch 83-84 is closed, the reactance tube is under the control of an audio modulation source. The audio modulation source comprises any desired type of microphone 93 which is connected across the primary winding 92 of input transformer 91. A negative biasing source 94 is included in circuit with the microphone. The secondary winding 90 is connected between contact point 84 and ground. The audio modulation source has its modulation voltage applied to control grid 77, and the plate to cathode impedance of tube 70 will have its magnitude varied in accordance with the intensity and frequency rate of the audio modulations. In this case the circuit S functions as the oscillator tank circuit of tubes 5 and 6. These tubes now function as oscillator tubes having parallel grids with plates grounded for radio frequency currents. Switch 17-25 applies sufficiently high positive potential to the plates of these tubes so that they readily act as oscillators. In the reception position of switch arm 17, the slider 18 has been adjusted to reduce the high voltage to be applied to plates 10-10'.

Opening of switch 50-52 renders the quench oscillator inoperative. The oscillations developed across circuit S will be varied in frequency in accordance with the amplitude of the audio modulation voltage from source 93 and the rate of frequency variation will be a function of the modulation frequencies per se. It will be recognized that the frequency modulation process per se is of a type well known to those skilled in the art. If desired, the switch arms 83, 17 and 50 can be mechanically coupled for unicontrol adjustment. The frequency modulated oscillations developed at circuit S are radiated from the antenna 1. When transmission is employed the switch arm 32 may be left wherever it is, since it does not affect the tubes 5 and 6 during transmission.

There are several advantages secured by this transceiver system. Super-regeneration is employed for either AM or FM signal reception. This means that high gain will be secured with weak signals fed to the detectors. The quench

energy is applied to the detector plates. This prevents spurious oscillations that would otherwise arise if the quench energy were applied to the detector grids. The AM reception may proceed even with tube 70 in circuit; it is only necessary to throw switch arm 32 into push-push position. This means that a minimum of operational adjustments are required in the field. For transmission it is merely required to actuate a common actuator for the switch arms 83—50—17. The very same reactance tube 70 and detector tubes 5 and 6 may then be employed to transmit. This is highly advantageous from the viewpoint of economy of parts, space and weight.

While I have indicated and described a system for carrying my invention into effect, it will be apparent to one skilled in the art that my invention is by no means limited to the particular system shown and described, but that many modifications may be made without departing from the scope of my invention as set forth in the appended claims.

What I claim is:

1. In a transceiver system, at least one electron discharge tube having a resonant signal input circuit, regenerative connections between the output and input electrodes of said tube, said connections including said resonant input circuit, a quench oscillator for applying superaudible frequency quench oscillations to an electrode of said tube, a modulation output circuit coupled to the output electrodes of said tube, a second electron discharge tube having its plate to cathode impedance connected across said resonant input circuit, means electrically associated with said second tube to cause said impedance to simulate a reactance across the resonant circuit, means applying said quench oscillations from said quench oscillator to an electrode of said second tube thereby to vary the magnitude of said reactance at said superaudible rate, a source of audio modulation energy, means for selectively rendering said quench oscillator inoperative, means for selectively rendering said first tube operative as an oscillator, and means for selectively disconnecting said second tube from the quench oscillator and connecting the second tube to said audio modulation source.

2. In a transceiver system for frequency modulated carrier wave energy, a pair of electron discharge tubes having a common signal input circuit adapted to be tuned to a desired carrier frequency, regenerative circuit connections between said tubes and said common input circuit, a modulation output circuit coupled to the output electrodes of said tubes, a quench oscillator adapted to produce oscillations at a superaudible frequency, means for applying said quench oscillations to the output electrodes of said tubes in alternate manner thereby to provide super-regenerative detection by said pair of tubes, a reactance tube having its cathode to plate impedance connected in shunt across said input circuit, means applying said quench oscillation energy to said reactance tube thereby to vary the magnitude of said impedance in a sense, and at a rate, such as to permit said signal input circuit to function as a discriminator of applied frequency modulation signals, a source of audio modulation signals, means for selectively connecting the said modulation source to the reactance tube and simultaneously disconnecting the latter from the quench oscillator, means rendering the quench oscillator ineffective, and additional means for rendering said pair of tubes op-

erable as oscillator tubes in response to connection of said audio modulation source to the reactance tube.

3. In combination with a super-regenerative detector circuit of the type comprising a pair of super-regenerative detector tubes having a common resonant input circuit and a quench oscillator for applying quench oscillations to said pair of tubes; the improvement which comprises 10 means for converting said super-regenerative detector tubes into a carrier oscillator, a reactance tube electrically associated with said resonant signal circuit for producing frequency variation of carrier oscillations produced by the carrier oscillator, 15 an audio modulation source for varying the effect of said reactance tube, and means for rendering said quench oscillator ineffective when said detector tubes function as said oscillator.

4. In combination, in a radio signalling system 20 having a resonant signal input circuit, an oscillating detector fed by said input circuit, a quench oscillator for applying quench oscillations to the detector, means for converting said detector into a carrier oscillator, a reactance tube electrically 25 associated with said resonant signal circuit for producing frequency variation of carrier oscillations produced by the carrier oscillator, an audio modulation source for varying the effect of said reactance tube, and means for rendering said quench oscillator ineffective when said detector functions as a carrier oscillator.

5. In combination with a super-regenerative detector having a resonant input circuit and a quench oscillator for applying quench oscillations 35 to the detector; the improvement which comprises means for converting said super-regenerative detector into a carrier oscillator, a reactance tube connected with said resonant signal circuit for producing frequency variation of carrier oscillations, 40 a source of modulation signals for varying the effect of said reactance tube, and means for rendering said quench oscillator ineffective when said detector functions as a carrier oscillator.

6. In a transceiver system, a detector having a resonant signal circuit, regenerative connections 45 between the detector output and input, said connections including said resonant signal circuit, a quench oscillator for applying quench frequency oscillations to the detector, a modulation output circuit coupled to the detector, an electron discharge tube having its plate to cathode impedance connected across said resonant circuit, means connected with said tube to cause said impedance to simulate a reactance across the resonant circuit, means applying said quench oscillations from said quench oscillator to an electrode of said tube thereby to vary the magnitude of said reactance, a source of modulation signal energy, means for selectively rendering said quench oscillator inoperative, means for selectively rendering said detector operative as a carrier oscillator, and means for selectively disconnecting said tube from the quench oscillator and connecting the tube to said modulation source.

7. In a transceiver system, at least one electron discharge tube having a resonant signal input circuit, regenerative connections between the output and input electrodes of said tube, said connections including said resonant input circuit, a quench oscillator for applying superaudible frequency quench oscillations to the anode electrode of said tube, a modulation output circuit coupled to the anode electrode of said tube, a second electron discharge tube having its plate to cathode impedance connected across said resonant input

circuit, means electrically associated with said second tube to cause said impedance to simulate a capacitative reactance across the resonant circuit, means applying said quench oscillations from said quench oscillator to a control electrode of said second tube thereby to vary the magnitude of said simulated reactance at said super-audible rate, a source of audio modulation energy, means for selectively rendering said quench oscillator inoperative, means for selectively rendering said first tube operative as an oscillator, and means for selectively disconnecting said second tube from the quench oscillator and connecting the second tube to said audio modulation source.

8. In a transceiver system, a pair of electron discharge tubes having a common signal input circuit adapted to be tuned to a desired carrier frequency, means alternately effective on said tubes to cause the latter to provide super-regenerative detection, a reactance tube having its cathode to plate impedance effectively in shunt across said input circuit, means responsive to said alternately effective means to control said reactance tube thereby to vary the magnitude of its impedance in a sense, and at a rate, such as to permit said signal input circuit to function as a discriminator, a source of audio modulation signals, means for selectively connecting the said modulation source to the reactance tube, and additional means for rendering said pair of tubes operable as oscillator tubes in response to connection of said audio modulation source to the reactance tube.

9. In combination with a super-regenerative detector circuit and a signal receiving antenna coupled thereto, means for converting said super-regenerative detector into a carrier oscillator, a reactance tube electrically associated with said

resonant signal circuit for producing frequency variation of carrier oscillations produced by the carrier oscillator, an audio modulation source for varying the effect of said reactance tube, and said 5 antenna functioning to radiate said frequency-variable oscillations.

10. In combination, in a radio signalling system having a resonant signal input circuit, an oscillating detector fed by said input circuit, 10 means for rendering the detector operative as a super-regenerative detector, means for converting said detector into a carrier oscillator, means electrically associated with said resonant signal circuit for producing frequency variation of carrier oscillations produced by the carrier oscillator, an audio modulation source for varying the effect of laid last means, and means for rendering said first means ineffective when said detector functions as a carrier oscillator.
11. In combination with a super-regenerative detector having a resonant signal input circuit, means for converting said super-regenerative detector into a carrier oscillator, means connected with said resonant signal input circuit for producing frequency variation of carrier oscillations, and a source of modulation signals for varying the effect of said means.
